WRINGER

Filed July 6, 1925

UNITED STATES PATENT OFFICE

WILLIAM ROBERTSON, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed July 6, 1925. Serial No. 41,568.

It is desirable in the formation of wringers, particularly such wringers as are used for power washers to provide them with a rigid frame. One reason for this is that most of such wringers are supported at one end of the frame so that they may be swung into and out of position. The present invention is designed in a simple and convenient manner to form the frame of greater rigidity than is ordinarily possible and arrange it so that the parts may be readily removed or detached for renewal. The invention also contemplates an improvement in the safety release device with which the wringer is provided. The invention also contemplates an improved means for locking a reversible drip board in its operative position. Other features and details of the invention will appear from the specification and claim.

The invention is illustrated in the accompanying drawings as follows:

Fig. 1 shows a front elevation of the wringer.

Fig. 2 an end elevation.

Fig. 3 a sectional view of the wringer with the parts partially detached showing a method of assembly.

Fig. 4 a plan view of the frame with the top removed.

Fig. 5 a view of the cam mechanism of the safety release, being in section on the line 5-5 in Fig. 1.

The wringer frame is cast in one piece and provided with the side stiles 1 of box section connected by the bottom bar 2 and top bars 3, the top bars 3 being in the form of plates at the front and back face of the frame leaving an opening 4 through the top.

The stiles are hollow having guide openings 4 extending from top to bottom of these stiles with inwardly extending ribs 5 along the insides of the guides. At the driving end of the roll the outer wall of the stile is closed at 6 with a perforation 6a for the drive shaft. At the gear side of the rolls ribs 7 extend inwardly from the face walls and a gear box 8 is formed on the end face of the stile.

A rod 10 of a lower roll 11 has its driving

end provided with a driving socket 12 and its gear end provided with a gear 13. It is assembled as shown in Fig. 3 by putting the driving end through the perforation 6a, moving the gear 13 through the top end of the gear box, the rod 10 extending down between the ribs 5 and 7. The rod rests in the journals 10a which rest on the bottoms 4a of the stiles. An upper rod 14 carries an upper roll 15 and is provided with a gear 16 meshing with the gear 13. It is assembled by moving directly down in a vertical direction, the roll passing between the plates 3 and the rod between the ribs on the opposite faces of the stile, the gear moving into the gear box through its upper open end. Bearings 17 are slipped into the open upper ends of the guides 4 into position on the top of the rod 14 and a tension spring 18 is placed between the ribs 5 on top of the bearing block 17. A detachable top 19 is provided. The upper ends of the stiles 1 have ears 20 and the top 19 has perforated ears 21 which extend over the ears 20 and a hinge pin 22 extends through the perforations in the ears 20 and 21 hinging the top in place at one end. At the opposite end a pin 23 is provided with a thumb nut 23a which permits of its ready removal so that the top may be swung up to the position shown in Fig. 3 to permit the detachment of the rolls, or different parts of the wringer. The top forms a housing covering all the openings in the top of the wringer, the top being hollow so as to permit the upper part of the spring 18 to extend into it. The top has an extension 24 which extends over and closes the top of the gear box.

A release bar 19a has a depending sleeve 19b which extends through an opening 19c in the top bar. The perforation 19c has axial slots 19d through which projections 19e slide, the projections 19e operating upon cams 19f on the under side of the top bar. A tension screw 19g extends through the sleeve 19b into a socket 19h on the tension bar. The cams 19f are formed of a separate piece as malleable iron and are secured in the top bar, which is ordinarily made of aluminum, in the casting operation as shown

in section in Fig. 5. This gives a bearing surface of sufficient hardness to sustain the pressure of the projections 19e in a simple and efficient manner. Heretofore the entire sleeve has ordinarily been secured to the top of an aluminum top bar making a rather unsightly construction and also one requiring extra finishing to make it match the aluminum structure.

10 The details of the release mechanism, other than the forming of the cam block, follow the construction shown in the Misner Reissue Patent #15,865, June 24th, 1924.

15 Drain board pins 25 extend inwardly from the lower ends of the side stiles and a drain board 26 has a flange 27 which operates on the pin 25, the flange being provided with the small sockets 28 and stops 29 to limit its movement to each reverse position. Difficultly has been experienced in securely locking this board in a simple and efficient manner in its reversed positions. This is accomplished in the present instance by fingers 30 pivotally mounted at each side of the 20 frame on ears 31 by means of pins 32. The finger 30 has its bottom eccentrically formed relatively to the pivot, forming a camming engagement with the drip board as it is swung on its pivot against the drip board, 25 30 the drip board resting on the pins 25 and the bottom bar 2 being engaged between these two points of support by the cam finger 30 securely locks it in this position, the tendency of the cam finger being to wedge itself 35 against the board and tighten with any movement of the board.

What I claim as new is:—

In a wringer, the combination of a frame comprising side stiles and a bottom bar, the 40 side stiles having guideways, one of said side stiles having the upper part of the outer face of the guide-way closed and provided with a shaft perforation; and wringer rolls mounted in the frame, one of said rolls having 45 a driving rod extending through the perforation in the side stile in the assembled wringer, said rolls being insertable from the top of the wringer.

In testimony whereof I have hereunto set my hand.

WILLIAM ROBERTSON.
